UNITED STATES PATENT OFFICE

OSCAR BITCHMAN, OF HABANA, CUBA

SPARK-PLUG MOUNTING

Application filed October 8, 1929. Serial No. 398,215.

The present invention is directed to improvements in spark plug mountings.

The primary object of the invention is to provide a device of this character so constructed that when the plug is removed the plug opening of the cylinder will be closed to prevent the escape of explosive gases from the cylinder, thereby preventing any possibility of an explosion.

Another object of the invention is to provide a device of this character constructed in such manner that when one plug of the series or set is removed for replacement or repair it will not be necessary to stop the engine.

Another object of the invention is to provide a mounting of this character so constructed that the plug will be housed and protected against collection of oil and carbon thereon, thereby maintaining the engine at a high point of efficiency.

Another object of the invention is to provide a device of this character so constructed that it can be operated or manipulated to permit removal and replacement of a plug in a comparatively short time.

Another object of the invention is to provide a device of this character so constructed and arranged in such manner that the spark plug opening of the cylinder will be effectively closed so as to eliminate noise while the spark plug is being changed, it being obvious that should the gas under pressure in the cylinder be discharged therefrom, considerable noise will result.

Another object of the invention is to provide a device of this kind which is exceedingly simple in construction, efficient in operation, durable, and one which can be manufactured at a minimum cost.

With these and other objects in view, this invention resides in the novel features of construction, formation, combination and arrangement of parts to be hereinafter more fully described, claimed and illustrated in the accompanying drawings, in which:

Figure 1 is a vertical central sectional view through the device, showing it in position upon a portion of a cylinder.

Figure 2 is a similar view showing the

mounting in position to close the plug opening.

Figure 3 is a sectional view on the line 3—3 of Figure 1.

Figure 4 is a perspective view of the plug 55 and ring in non-assembled relationship.

Figure 5 is a vertical sectional view through the plug, showing the same mounted in a bushing.

Referring to the drawings, 1 designates 60 a portion of an internal combustion engine cylinder, in this instance the head, and in which is formed, as is customary, the threaded opening 2. The inner surface of the head is provided with a conical seat 3, 65 the purpose of which will be later explained.

The mounting includes an exteriorly threaded hollow plug 4 having a square tool engaging head 5 upon its upper end, 70 whereby a suitable tool may be employed for applying the plug to the cylinder or removing the same therefrom.

The plug is closed at its lower end and has its wall formed with a plurality of radially disposed ports 6, preferably seven in number.

The plug is exteriorly threaded upon its lower end, as at 7, and threaded thereon is the ring which constitutes a valve 8 adapted 80 to engage the seat 3 when the spark plug 9 is removed. The spark plug 9 is of conventional form and is threaded in the plug 4, the electrodes thereof being located slightly above the plane of the ports 6. 85 When the spark plug 9 is engaged in the plug 4, a chamber A is provided between the spark plug and the closed end of the plug 4, so that when the compressed charge of fuel enters this chamber it will be highly compressed. Obviously, when ignition of the gas takes place in the chamber A, the flame will pass through the ports 6 and ignite the compressed charge within the cylinder, and owing to the restricted nature of the port 6, the flame ejected therefrom will be in blast-like form, thus insuring proper ignition of the gases within the cylinder. In this manner, the explosion will 95

100

be very effective in operating the piston within the cylinder.

The combined cross sectional area of the lower end of the plug 4 and the ring 8 will provide a efficient deflector to prevent oil from entering the chamber A through the ports 6, and should any carbon collect within the ports 6, the blast of the flame will discharge the same, thus maintaining the chamber A and the spark plug in a thoroughly clean condition.

When it is desired to remove the spark plug 9 it is only necessary to place the proper tool upon the head 5 and rotate the plug to thread the same upwardly in the opening 2, whereupon the ports 6 will be confined in the opening 2, and the ring 8 will engage the seat 3, thus effectively sealing the cylinder and preventing gases therein escaping to the atmosphere while the plug is being removed or replaced. After the spark plug has been replaced, the rotation of the plug 4 is reversed so that the ring 8 will disengage the seat 3 and the ports 6 will open freely into the cylinder.

The ring 8 is threaded upon the plug 4 in a left hand direction so that when the ring engages the seat, the tendency will be to more firmly secure the ring upon the plug.

The ring 8 has a beveled upper face 10 in order to assume a leaf-proof joint when the ring is engaged in the seat 3.

The ring 8 is of greater diameter than the opening 2 and is obviously applied to the plug after said plug has been threaded in said opening.

Owing to the multiplicity of ports 6, a number of jets of flame will be emitted from the chamber A to more effectively ignite the compressed charge of gas in the combustion chamber of the cylinder.

In Figure 5, the plug 4 is shown engaged in a bushing 11 so that the plug can be applied to a marine engine.

From the foregoing, it is thought that the operation and many advantages of the herein described invention will be apparent to those skilled in the art without further description and it will be understood that various changes in size, shape, proportion, and minor details of construction may be resorted to without departing from the spirit or sacrificing any of the advantages of the invention.

What is claimed is:

An internal combustion engine having a threaded opening in its wall communicating with a combustion chamber, a hollow plug open at its upper end and closed at its inner end, the plug being externally threaded for engagement with the threads of the opening and having its inner end portion projecting into the combustion chamber when the plug is screwed tightly into the opening, side ports being formed through the walls of the

plug adjacent its closed inner end, the wall of the engine being formed with an annular seat about the inner end of its opening, a collar about said plug between the ports and the inner end of the plug, the ports being adapted to be closed by the walls of the plug receiving opening when the plug is screwed outwardly and the collar constituting a valve head engageable with the seat when the plug is screwed outwardly to tightly seal the inner end of the plug receiving opening about the plug, and a spark plug removably mounted in said plug above the ports and removable through the open upper end thereof.

In testimony whereof I affix my signature.

OSCAR BITCHMAN. [L. S.]
